PROJECTILE

Willing B. Foulke, Media, Pa., assignor to Hercules Powder Company, Wilmington, Del., a corporation of Delaware

Application March 14, 1935, Serial No. 10,974

9 Claims. (CL. 102—26)

This invention relates to an improvement in projectiles and more particularly to projectiles or bullets for small arms, and more particularly for rifles, machine guns, anti-tank guns, and the like.

For many years rifle bullets were formed from lead or lead alloy. However, the lead or lead alloy bullet was found unsatisfactory for use at high muzzle velocities and a bullet comprising a lead or lead alloy core provided with a copper alloy jacket was substituted and has remained in general use up to the present time.

In the designing of a bullet a large number of factors must be taken into consideration with reference to the effect of pressures, developed on burning of the powder charge, upon the bullet within the barrel of the gun and the effect of the atmosphere upon the bullet after it leaves the barrel, all with a view to obtaining a maximum of efficiency from the standpoint of range, penetration and accuracy.

It is recognized that the most modern military rifle bullet, which may be exemplified by the 173 grain 30 cal. Springfield rifle bullet of the so-called 9 degree boat tail type and comprising a lead alloy core jacketed with a copper alloy, will not stand muzzle velocities above about 3000 feet per second.

As is well known, a rifle barrel, extending from a chamber adapted to receive a cartridge, is grooved or rifled in order that the bullet forced through the barrel by the gas pressure developed by the burning of gun powder will be given a rotary motion so that on leaving the barrel it will not gyrate. In usual practice a progressive or slow burning gun powder is used to the end that pressure is built up behind the bullet as it travels through the barrel to the end that it will proceed with increasing velocity through the barrel.

In passing through a rifle barrel the bullet, which is of a diameter equal to the maximum diameter, groove diameter, of the barrel from the bottoms of the rifling grooves, is initially engraved or threaded by the rifling to conform therewith throughout its cylindrical body portion, as compared with its point and tail portions, and is, as it were, squeezed through the barrel and discharged therefrom with a rotative motion, as well as a forward velocity.

In the barrel the bullet is subjected to friction and, due to the great pressure behind it, has a tendency to fill out into the barrel, or upset, where the barrel has increased in diameter due to the increasing pressure. Again, there is a

tendency for a bullet to elongate on entering the rifling from the action of gas escaping around it, which subjects its cylindrical body portion as well as its base to tremendous pressure, which causes the point, not in the high pressure area, to progress faster than the base, or, in other words, for the bullet to be, as it were, extruded in the barrel and miss the rifling, with the result that the gas leakage increases with loss of velocity to the bullet and accuracy decreases due to lack of spin.

Due to the friction, upsetting or elongation of the bullet and also due to various gas leaks around the shell or cartridge, to heat losses by radiation, convection and absorption from and by the rifle and to a degree by the bullet, to the air resistance in the barrel and to the rotative inertia of the bullet, large loss of energy made available by the burning of the powder charge occurs, with the result that bullet velocity is limited and accuracy is below a maximum.

The maximum muzzle velocity of the present modern bullet is further limited by its lack of capacity to resist the forces acting upon it at velocities such that the forces, tending, more particularly, to upset the bullet, are in excess of the elastic limit of the copper alloy jacket; and by the necessity for entering the bullet into the rifling with reference to its rotative inertia without stripping.

In the atmosphere the bullet in its flight is hindered, or its energy absorbed, by the necessity for displacing air as it progresses, by the vacuum formed at its base due to its rapid flight, by the skin friction between the bullet and the air, by a boundary layer of air which the bullet carries, and by its gyration in the air, which results from its deformation under the forces acting upon it in the barrel or arising from a rotative and/or forward muzzle velocity resulting in forces exceeding the elastic limit of the material from which it is formed.

Now in accordance with this invention there is provided a bullet, more especially for small arms, as rifles, machine guns, anti-tank guns, and the like, which is of a novel design such that losses of energy within and without the barrel suffered in connection with use of the most modern bullets heretofore known will be minimized and, at the same time, such as to permit of greatly increased velocities from the energy developed by the powder charges used heretofore and with use of heavier powder charges than were practical for use with prior bullets.

The bullet in accordance with this invention will, generally speaking, be formed from a ma-

material having an elastic limit in excess of the forces acting to upset or elongate it and to deform it in its passage through the barrel and will have a form such as to largely eliminate the negative forces tending to retard its flight.

More particularly, the bullet in accordance with this invention will comprise a body portion, a tail or base portion of suitable shape and a point of suitable shape, and will be provided with a forward and a rear rifling band.

Essentially, the rifling bands will be positioned so that the rear edge of the forward rifling band and the forward edge of the rear band will be equidistant from the center of mass of the bullet, and the diameter of the bullet throughout will be less than the bore diameter by an amount greater than the difference between the bore and groove diameters.

Having now indicated in a general way the nature and purpose of this invention, I will now proceed to a detailed description thereof with reference to the accompanying drawing, in which:

Figure 1 is a side view of a bullet embodying this invention.

Figure 2 is a side view of the bullet, shown in Figure 1, in flight.

Figure 3 is a cross-sectional view of a rifle barrel with the relative diameter of the barrel and bullet exemplified.

The bullet illustrated comprises a body A, a point B, and a base or tail C and is equipped with a forward rifling band D and rear band D', which is grooved as at e.

The point B of the bullet may be of any desired shape. Thus, for example, the point may be ogival, as shown in full lines, Figure 1, or it may have the form shown in dotted lines Figure 1.

The base or tail C may be of any desired shape. Thus, for example, it may have the so-called boat tail shape as shown.

The bullet may be constructed of any suitable material having an elastic limit such as to withstand the forces acting upon it at high velocities. For example, the bullet may be formed from a cupro-nickel alloy having various proportions of copper and nickel, depending upon the type of arm or upon the caliber or shape of the bullet.

The rifling bands D and D' may be made of any suitable material adapted to take the rifling of a gun barrel and the bands may be formed separately or integral with the body of the bullet, depending upon the material from which the bullet is formed and the anticipated velocities. Thus, for example, the bands may be formed of gilding metal, Monel metal, cupro-nickel alloy, etc.

Where, for example, the bullet body is formed from steel, the rifling bands will be formed separately and applied to the body, shoulders f, g being formed to prevent slipping of the bands respectively. The shoulder f will be lower than the shoulder g and the band D' will be bored to pass over the shoulder f for application. Again, where the bullet is formed from a metal, such as Monel metal, the rifling bands may be formed integral with the body, without the necessity for forming the shoulders f and g by, for example, turning the bullet and bands to form from a blank.

As has been indicated, the bands, whether they are formed separately and applied to the body of the bullet, or formed integrally therewith, will be so positioned that the rear edge d

of the forward band and the front edge d' of the rear band will be spaced equidistant from the center of mass of the bullet, indicated at X, Figure 1.

The body of the bullet will, as has been indicated, be of a diameter less than the minimum diameter of the gun barrel for which it is adapted, i. e. of a diameter less than the diameter of the barrel between the lands of the rifling. Thus, the body of the bullet will be of a diameter such that it will be entirely clear of the barrel, the only engagement therewith being made by the rifling bands D, D'. Preferably, as has been indicated, the body of the bullet will be less in diameter than the difference in the diameters of the barrel, i. e. between the lands and between the grooves; and even more preferably the diameter of the bullet will be not more than two-thirds of the bore diameter of the barrel, i. e. between the lands.

As illustrative, for example, a practical comparison between the diameter of a .30 cal. Springfield rifle bullet and the diameter of the rifle barrel is shown in Figure 3, in which H indicates a rifle barrel, the lands and grooves of the rifling being indicated by i and j, respectively. A indicates the body of a bullet within the barrel, the rifling bands on the bullet being omitted, it being thought unnecessary to illustrate their well known relationship with the rifling. In the showing of Figure 3, the rifle will, for example, have a maximum diameter, between the grooves, of about .309 inch and a minimum diameter, between the lands, of about .301 inch. It follows that the groove depth is .004 inch and that the difference in diameters is .008 inch. Now, the diameter of the bullet in accordance with this invention will be, for example, .290 inch, i. e. .011 inch less than .301 inch, the minimum diameter of the barrel, i. e. between the lands. As has been indicated, the body of the bullet will desirably be considerably less in diameter than the minimum diameter of the barrel, as, for example, of a diameter two-thirds or less of the minimum or bore diameter of the barrel. For example, in the illustration given with reference to Figure 3, the diameter of the body of the bullet may be .200 inch or less.

In consequence of the material, form and relative proportions with respect to the rifle barrel of the bullet in accordance with this invention, the bullet may be subjected to greatly increased pressures in the rifle barrel and will withstand greatly increased velocities.

On the firing of the bullet in accordance with this invention, the forward rifling band D, will enter and be engaged by the rifling while the bullet is traveling at its slowest speed and has as a consequence a low turning moment. As a consequence, the forward band may be relatively short longitudinally and due to its shortness will be readily engraved and enter the rifling without stripping at the slow initial speed and low turning moments of the bullet.

By the time that the forward band D has engaged with the rifling and before the engagement of the rear band D', gas will have escaped past the base of the bullet and will enter the barrel where, since the pressure will be relatively low, it will be stopped by and readily held by the forward band which has taken the rifling.

The rear band will engage the rifling shortly after engagement by the forward band, and it will be noted that the rear band will engage on a spiral generated by the forward band. Con-

sequently, stripping effect on the rear band due to jump will be avoided.

The rear band, since it must pick up the main load of the turning moment of the bullet as the maximum gas pressure is exerted and the bullet increases in velocity, is made of greater extent longitudinally than the forward band. The rear band is desirably also provided with the groove *e* in order that the band may be wiped toward the rear by the rifling in two steps without deforming the band throughout its entire longitudinal extension. The groove *e* also acts as a secondary gas seal.

The gas entering the barrel ahead of the rear band *D'* will be trapped between the bands and gas will also be trapped in the groove *e*. The pressure of the trapped gas will be lower than the ultimate pressure behind the rear band. However, it will offset the ultimate pressure and reduce the tendency of maximum ultimate pressures to upset the rear band. Again, the pressure of gas trapped between the front and rear bands will offset the tendency of pressure developed in the barrel ahead of the bullet (from the column of air in the barrel) to upset the forward band.

Since the diameter of the body of the bullet in accordance with this invention is substantially less than the minimum diameter of the barrel, its turning moment is low and the rifling bands, since they as a consequence extend a substantial distance from the body of the bullet, have a substantial leverage through which to exert a turning force on the bullet. Further, the bands are of relatively small longitudinal extent with reference to the length of the body of the bullet and as a consequence since the body is entirely free of the barrel the frictional resistance to the bullet's passage through the barrel is at a minimum.

The bullet in accordance with this invention will not upset or elongate in the barrel and as a consequence leaves the barrel without deformation from its true shape.

The bullet on leaving the barrel will travel through the air with a rotary motion and, since with any type of bullet it has been found impossible to have the center of gravity of the bullet exactly on the axis of the bore, the bullet will travel on a spiral. However, in the case of the bullet according to this invention, the angle of the spiral will be at a minimum, due to the lack of deformation in the barrel (upset and elongation) taken with accuracy in formation of the bullet.

The action of the bullet in its travel after leaving the muzzle is indicated in Figure 2, from which it will be noted that the point *B* entering the air *l* ahead of it at high velocity drives the air aside and forms a partial vacuum about the point of the bullet, which offsets the effect of the partial vacuum area *o* behind the base. A boundary layer of air, indicated at *m*, however, tends to travel with the bullet about its point, behind the point *n* at which the air flows off the body, and to retard its velocity and interfere with its accuracy. This boundary layer of air is removed in the initial flight of the bullet by the action of the engraving by the rifling on the forward band *D*, since the engraved band acts in effect as a high speed centrifugal pump and discharges the boundary layer, as indicated by the lines *p*.

It will be appreciated that the projectile or bullet of this invention is contemplated as capa-

ble of withstanding velocities very substantially higher than are obtained with bullets heretofore known and that the bullet, aside from its formation and the formation of its rifling bands from material having an elastic limit greater than the forces acting on the bullet and bands, respectively, derives its capacity essentially from the relative diameter of its body with respect to the minimum diameter of the barrel through which it is to be fired, and from the arrangement and location of the rifling bands.

It will be appreciated that the particular material of which the bullet and bands are constructed will be selected in view of the velocity and hence the forces to which it is to be subjected.

Generally, it will be appreciated that the bullet in accordance with this invention is contemplated for use in any calibre and type of gun for which it may be adaptable.

What I claim and desire to protect by Letters Patent is:

1. A projectile adapted for high velocities comprising a body portion and rifling bands having a high tensile strength, the body portion being throughout of a diameter less than the bore diameter of the barrel of the gun for which it is intended by an amount in excess of the difference between the groove and bore diameters of the barrel, and shoulders on the body portion in engagement with the bands to prevent rearward movement thereof.

2. A projectile adapted for high velocities comprising a body portion and rifling bands formed from materials having elastic limits in excess of the forces acting thereon on firing, the body portion being throughout of a diameter less than the bore diameter of the barrel of the gun for which it is intended by an amount in excess of the difference between the groove and bore diameters of the barrel, and shoulders on the body portion in engagement with the bands to prevent rearward movement thereof.

3. A projectile adapted for high velocities comprising a body portion and rifling bands having a high tensile strength, the body portion being throughout of a diameter less than two thirds of the bore diameter of the barrel of the gun for which it is intended, and shoulders on the body portion in engagement with the bands to prevent rearward movement thereof.

4. A projectile adapted for high velocities comprising a body portion and rifling bands having a high tensile strength, the body portion being formed from a metal from the group consisting of steel Monel metal and copper-nickel alloy and being throughout of a diameter less than the bore diameter of the barrel of the gun for which it is intended by an amount in excess of the difference between the groove and bore diameters of the barrel, and shoulders on the body portion in engagement with the bands to prevent rearward movement thereof.

5. A projectile adapted for high velocities comprising a body portion formed from materials having elastic limits in excess of the forces acting thereon on firing, the body portion being throughout of a diameter less than the bore diameter of the barrel of the gun for which it is intended by an amount in excess of the difference between the groove and bore diameters of the barrel and the rifling bands having a high tensile strength and comprising a front band and a rear band, the front edge of the rear band and the rear edge front band being spaced equidistant

- from the center of mass of the projectile, and shoulders on the body portion in engagement with the bands to prevent rearward movement thereof.
5. 6. A projectile adapted for high velocities comprising a body portion formed from materials having elastic limits in excess of the forces acting thereon on firing, the body portion being throughout of a diameter less than the bore diameter of the barrel of the gun for which it is intended by an amount in excess of the difference between the groove and bore diameters of the barrel and the rifling bands having a high tensile strength and comprising a front band and a rear band, the front band being of substantially less extent longitudinally than the rear band, and shoulders on the body portion in engagement with the bands to prevent rearward movement thereof.
10. 7. A projectile adapted for high velocities comprising a body portion formed from materials having elastic limits in excess of the forces acting thereon on firing, the body portion being throughout of a diameter less than the bore diameter of the barrel of the gun for which it is intended by an amount in excess of the difference between the groove and bore diameters of the barrel and the rifling bands having a high tensile
15. strength and comprising a front band and a rear band, the rear band being of substantially greater extent longitudinally than the front band and having a circumferential groove dividing its surface into two sections, and shoulders on the body portion in engagement with the bands to prevent rearward movement thereof.
8. A projectile adapted for high velocities comprising a body portion and rifling bands having a high tensile strength, the body portion being formed of steel and being throughout of a diameter less than the minimum bore of the barrel of the gun for which it is intended by an amount in excess of the difference between the groove and bore diameters of the barrel and the rifling bands being formed from a cupro-nickel alloy.
9. A projectile adapted for high velocities comprising a body portion and rifling bands having a high tensile strength integral with the body, the body portion and the rifling bands being formed of Monel metal and the body portion being throughout of a diameter less than the bore diameter of the barrel of the gun for which it is intended by an amount in excess of the difference between the groove and bore diameters of the barrel.

WILLING B. FOULKE.
